By his Atty:

UNITED STATES PATENT OFFICE.

JOHN ASKEW, OF LEAMINGTON, CANADA.

HINGE-ROLLER GATE.

SPECIFICATION forming part of Letters Patent No. 588,374, dated August 17, 1897.

Application filed August 24, 1896. Serial No. 603,708. (No model.) Patented in Canada April 28, 1896, No. 52,130.

To all whom it may concern:

Be it known that I, JOHN ASKEW, a subject of the Queen of Great Britain, residing at Leamington, Province of Ontario, Dominion of Canada, have invented certain new and useful Improvements in Hinge-Roller Gates, (for which I have obtained a patent in Canada, No. 52,130, dated April 28, 1896,) of which the following is a specification.

My invention relates to improvements in farm-gates which are supported upon a hinged roller in such manner that the gate may be rolled lengthwise upon its hinged support until the latter is brought midway upon the gate to allow the gate to be balanced thereon and easily swung upon its hinge-support to widen the gate-opening or to close the gate-opening partly by a swinging and partly by a sliding movement of the gate. Gates of this class have been long in general use, but have been defective in the hinge connection, thus precluding its use for many purposes or requirements.

My invention consists in certain details of construction, comprising a swiveled pulley, a pulley strap and bolt, and a holder secured to the post in a novel manner, and also in stop-blocks of novel construction secured to the longitudinal plates or members of the gate, which will receive the shock or impact of the gate, and thus relieve the hinge-support of undue strain.

In the accompanying drawings, which illustrate my invention, Figure 1 is a side elevation of a gate equipped with my improved sliding hinge-support, the gate shown partly open; Fig. 2, a side elevation of the upper part of the gate-supporting post and hinge connection enlarged; Fig. 3, a fragment of the latch-post of the gate and latch-keeper secured thereto, and Fig. 4 a fragment of one of the gate standards and rails with my anti-percussion stop-block secured thereto.

The gate-panel A is supported upon a gate-supporting post B to slide longitudinally and also to swing thereon, and is provided at its free swinging end with a plate a, having a projecting end a', which forms a latch and engages with a keeper C upon a latch-post D when the gate is closed. The keeper C consists in an elbow or angle-plate having a bolt c' formed integral therewith to pass through

the said post and be secured thereon by means of a nut c², fitted upon the threaded end of said bolt.

The gate-panel A is supported upon the post B in the following-described manner: A rectangular block of hard wood forms the hinge-holder E and is fitted into a mortise in the post B and secured thereon by a bolt e, passed through said post and holder and secured thereto by a nut e', fitted upon the end of said bolt to bear upon the post on the opposite side of the hinge-holder E and securely clamp the said holder upon the post in a simple, strong, and inexpensive manner. The hinge-holder E is bored vertically at the middle of its projecting end e² to receive a bolt f, welded or made fast to a stirrup-strap F, the lower ends of which carry an axle-bolt f', upon which is supported a roller G to turn freely thereon and be held between the plates of the stirrup-strap. A washer and split key f² upon the upper end of the pivot-bolt f serves to hold the swivel-hinge securely upon the hinge-holder E, to be suspended therefrom. The stirrup-strap F is of sufficient length to receive the longitudinal plate b (preferably the plate next below the top plate of the gate) therein and allow the gate to be supported upon and be moved freely lengthwise upon the supporting-roller G.

The plates b² of the upright end post A' and middle post A² of the gate-panel A are bolted to the opposite sides of the longitudinal gate-plates b', and between said plates b² and above the plate b' is supported the tongue h of a sliding percussion-block H, one of said blocks being secured to the inner sides both of the end post A' and the middle post A² and in such position that the ends of said blocks will strike the hinge-holder E at the end of the movement of the gate and relieve it of shock or jar incident thereto. The blocks H have a metal spring-plate I interposed between the shoulders thereof and the post-plates, and a slot h' in the tongue h receives a bolt h², which passes through the gate-plates and through the said slot and holds the block H securely in place and also admits of a sliding movement to receive the impact of the block against the hinge-holder. A gate thus supported will withstand severe usage without breaking down or wrenching

the hinged roller from the gate-supporting post.

I claim as my invention and desire to secure by Letters Patent—

5 In a swivel sliding gate, the combination with the supporting-posts and gate-panel, of a hinge-holder secured to the supporting-post to project therefrom and spring-actuated percussion-blocks supported upon the gate-panel

to relieve the gate and hinge-holder of shock, substantially as described.

In testimony that I claim the foregoing as my invention I have signed my name in the presence of two subscribing witnesses.

JOHN ASKEW.
